UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed October 27, 1921. Serial No. 510,699.

My invention relates to mining apparatus. It has for its object to provide an improved mining apparatus and more especially an improved mining apparatus comprising improved means for handling cuttings whereby the cuttings are delivered at a point removed from the face and out of the way of the coal. A further object of my invention is to provide an improved longwall mechanism wherein through the use of improved cuttings handling mechanism, the above results are obtained at the same time that the machine is maintained of such width as to enable it to work at a close-propped face. A still further object of my invention is to provide an improved cuttings handling mechanism adapted to be applied to a standard mining machine in an improved manner and cooperate therewith to distribute the cuttings as above described. These and other advantages of my improved construction will, however, hereinafter more fully appear.

In the accompanying drawings I have shown for purposes of illustration one embodiment which my invention may assume in practice, the same for these purposes being shown as applied to a longwall machine.

In these drawings,

Fig. 1 is a plan view of a mining machine of the longwall type equipped with this form of my improvement, the slack shoveler casing being shown in section to facilitate illustration.

Fig. 2 is a side elevation of a slack shoveler mechanism, the side casing being removed and parts broken away.

Fig. 3 is an end view of the slack shoveler mechanism, a portion of the casing being broken away.

Fig. 4 is an enlarged sectional view on line 4—4 of Fig. 2.

Fig. 5 is a similar view on line 5—5 of Fig. 3.

In this illustrative construction, I have shown a mining machine of a standard longwall type and comprising a casing 1 carrying at one end thereof a pivoted cutter bar 2 provided with a usual cutter chain 3 and also carrying suitable machine feeding mechanism which may be of any desired type and herein is of the flexible chain propelled type, the same including a feed operating member 4 on the opposite end of the casing from the bar and cooperating with a feed chain 5 in a well known manner, it being understood that the

cutter chain 3 and the feed operating member 4 are both driven from a motor 6 in the casing 1 through usual driving connections not shown. As in a usual construction this machine is adapted to have its bar 2 swung in under the face and then to be propelled along the face and relative to its flexible feeding member 5, upon rotation of the feed operating member 4 to undercut a face as the machine slides on its bottom on the mine bottom. During this operation, it will be understood that since the cutter chain 3 moves around the bar in the direction of the arrows, the cuttings therefrom will be delivered beneath the retreating end of the machine in such a manner as heretofore to require under certain conditions constant shoveling on the part of one man to keep the cuttings away from the bottom at a point adjacent the face, as should they be allowed to remain where the machine leaves them, these cuttings will be mixed with the lump coal which either falls down into the space previously occupied by the machine after the machine has undercut, or is thereafter shot down into that space.

In my improved construction, improved means are provided whereby these cuttings are handled mechanically and automatically in such a manner as to throw them out of the machine path and out of the space desired for the lump coal, my improved mechanism being so disposed relative to the machine as to be movable in the same path as the machine without increasing the depth thereof or in any way decreasing the ability of the machine to cut in a narrow strip between the face and the props. More specifically, it will be noted that operatively connected to the casing 1, herein to the rear head 7 thereof, is a cuttings unit generally indicated at 8 and herein comprising a casing 8 slidable on its bottom on the mine bottom and disposed during cutting in alignment with the casing 1 and on the opposite side of the bar 2 from the feed operating member 4. As shown, this casing carries a cuttings handling or shoveling member 9 disposed in front of the casing 8 near the bottom and just in rear of the head 7 and adjacent the delivering end of the chain 3. As shown, this member 9 has an open beveled side adjacent the mining machine and both ends open, one end herein preferably communicating with a slide 10 on the casing which is preferably curved and

widened as it approaches the member 9 to provide a free passage for cuttings to the shovel, while the other end is free to deliver the cuttings outside the path of the machine. 5 Operatively associated with the shovel 9 is improved means for operating that member, herein substantially in the manner of a manually operated shovel, this means comprising improved means for moving the member 9 10 toward and from the machine and improved means for tilting the shovel after it is withdrawn from its loading position.

We will first consider the means for moving the member 9 toward or from the machine. Herein it will be noted that a motor 11 is carried in a suitable casing on the casing 8, the same herein being disposed longitudinally thereof. This motor has a worm 12 operatively connected to the rear end of 20 its armature shaft, which worm in turn meshes with a worm gear 13 carried on a transverse shaft 14 journaled in suitable bearings 15 supported on the bottom of the casing 8, while the shaft 14 carries at one end a pinion 16 meshing with a cooperating pinion 17 on a parallel forwardly located longer shaft 18 likewise journaled in suitable bearings 19 supported on the bottom of the casing. 25 Herein it will be observed that outside each of these bearings 19 the shaft carries an eccentric disk 20 having a pin 21 adjacent its periphery and received in an elongated slot 22 on one end of a link 23 which is in turn pivoted at 24 to a cooperating upwardly disposed link 25 at a point preferably nearer the lower end thereof which is pivoted at 26 on the bottom of the casing 8. As shown herein, each of these links 25 is also pivoted at its upper end as through a slotted connection 27 to one end of a longitudinally disposed rod 28 passing through suitable guides 30 on the casing 8 and having its other end suitably connected to the machine head 7, herein by bolts 31. Thus, it will be observed that when 35 the armature of the motor 11 is rotated, the worm 12 and the connected gearing cause the disks 20 to operate through their linkage to swing the members 25 about their pivots and thereby move the casing 8 toward or 40 from the machine head 7 in such a manner as successively to project the shovel 9 into the cuttings and withdraw the loaded shovel therefrom.

Cooperating with this mechanism is also 55 improved mechanism for discharging the load from the shovel. Here it will be noted that the member 9 is pivoted at its outer edge at 32 to one end of the casing 8 and that the shovel 9 is provided with a side 33 of substantially triangular form so that as it is moved forward, a limit for the cuttings is provided while when the shovel is tilted about its pivot 32, the cuttings will move freely out 60 of the shovel and on to the bottom at a point adjacent the props. The mechanism for tilt-

ing the shovel herein includes a bevel pinion 34 carried on the opposite end of the shaft 14 from the pinion 16 and meshing with a cooperating bevel pinion 35 on the front end of a longitudinally extending stub shaft 36 70 journaled in suitable bearings 37 on the bottom of the casing 8. Herein a disk 38 similar to the disks 20 is connected to the rear end of this shaft 36 and this disk carries a pin 39 cooperating with a slot 40 in one end of a transversely disposed link 41 having a rack 42 on its opposite end movable in a swinging bearing 42' relative to a pinion 43 on a longitudinally disposed shaft 44 journaled in suitable bearings 45 supported on the casing 8 80 and herein having a pinion 46 on its front end meshing with a segmental rack 47 disposed about the shovel pivot 32 as a center and fixed to the side 33 of the shovel. Through this mechanism, which it will be 85 noted operates in timed relation with the mechanism for moving the cuttings forward and backward relative to the machine, the shovel member 9 is thrown from its lower dotted line position shown in Fig. 3 to its 90 upper dotted line position shown in that figure and back again as the casing 8 is near the rear limit of its travel, so that the cuttings are intermittently thrown from the shovel 9 between the props and entirely out of the 95 space which it is desired to reserve for the lump coal.

As a result of my improvement, it will be observed that the slack shoveling mechanism is exceedingly compact, the same being disposed within the lines of the machine in such a manner as in no way to interfere with the use of the machine, the mechanism instead being capable of being used with a machine wherever the machine may be used. It will 100 further be evident that through my improved construction and arrangement, the shoveling mechanism may be made relatively light as compared with the machine so that the movement of the machine will not be impeded, this 105 being especially true in view of the provision of a separate motor for supplying the power for the shoveling movements, although I do not consider that my invention is limited to the use of such a separate motor as obviously 110 under certain circumstances, the power may be derived from a convenient moving part of the mining machine. Attention is also directed to the fact that through my improved shoveling mechanism, the slack is handled 115 with substantially the same accuracy as by human hands, the movements of my improved shoveler member corresponding broadly to the movements of a shovel in the hands of an operator, all the well known difficulties of 120 conveyors or the like being thereby eliminated. It should also be noted that in my improved construction, the device may be attached to or removed from a mining machine 125 of standard construction whenever desired 130

and applied to standard machines in the field quickly and at relatively small expense.

While I have in this application specifically described one embodiment which my invention may assume in practice, it will be understood that this form of the same is shown for purposes of illustration and that the invention may be modified and embodied in various other forms without departing 10 from its spirit or the scope of the appended claims.

What I claim as new and desire to secure by Letters Patent is:

1. In a mining apparatus, kerf cutting mechanism movable along a face in which a kerf is being cut, and slack handling mechanism for moving slack laterally from the face and out of the path of the apparatus, said handling mechanism being connected to 15 said cutting mechanism and disposed wholly outside of and parallel to the face and laterally of the trailing edge of said cutting mechanism.

2. In a mining apparatus, kerf cutting mechanism movable along a face in which a kerf is being cut, and slack handling mechanism movable therewith and normally bodily movable as a unit relative thereto in one direction during operation thereof and disposed parallel to the face.

3. In a mining apparatus, kerf cutting mechanism movable along a face in which a kerf is being cut, and slack handling mechanism connected to said cutting mechanism 35 at the trailing end thereof and disposed parallel to, wholly outside of, and against the face for receiving the slack brought back from the kerf by said cutting mechanism and discharging the slack away from the 40 face and out of the path of the apparatus.

4. In a mining apparatus, kerf cutting mechanism movable along a face in which a kerf is being cut, and slack handling mechanism movable therewith and normally bodily movable as a unit relative thereto in one direction during operation thereof and disposed parallel to and against the face.

5. In a mining apparatus, a mining machine including kerf cutting mechanism movable along a face in which a kerf is being cut, and a trailing slack handling mechanism for discharging slack laterally away from the face and out of the path of the machine, said slack handling mechanism being disposed wholly outside of and parallel to the face and supported independently of said cutting mechanism at the trailing end thereof.

6. In a mining apparatus, a mining machine including a cutter chain carrying cutter bar, and a shovel mechanism connected to said machine including a reciprocal shovel element for receiving the cuttings therefrom and for discharging the cuttings laterally of 65 said shovel mechanism.

7. In a mining apparatus, a mining machine including a cutter chain carrying cutter bar, an automatically operating shovel mechanism connected to said machine including a pivoted shovel element for receiving the cuttings therefrom and for discharging the cuttings laterally of said shovel mechanism.

8. In a mining apparatus, a mining machine including kerf cutting mechanism movable along a face in which a kerf is being cut, a shovel member connected to said machine adjacent only the trailing edge of said kerf cutting mechanism and adjacent said face, and means for operating said shovel 75 member to discharge slack laterally of the face.

9. In a mining apparatus, a mining machine including kerf cutting mechanism movable along a face in which a kerf is being cut, a tiltable shovel member connected to said machine adjacent the face, and means for loading and unloading said shovel member with a vertical load, said shovel member being adapted to discharge said load away 85 from the face.

10. In a mining apparatus, a mining machine including kerf cutting mechanism movable along a face in which a kerf is being cut, and means connected to said machine for handling the slack created thereby including a shovel member, and means for reciprocating and tilting said shovel member to pick up and discharge the slack 90 away from the face.

11. In a mining apparatus, a mining machine including kerf cutting mechanism movable along a face in which a kerf is being cut, and means connected to said machine for handling the slack created thereby including a shovel member, and means for reciprocating 105 said shovel member and tilting it after withdrawal to pick up and discharge the slack away from the face.

12. In a mining apparatus, a mining machine including kerf cutting mechanism movable along a face in which a kerf is being cut, and means connected to said machine for handling the slack created thereby including a shovel member, and means for reciprocating 115 said shovel member and tilting it in opposite directions after a longitudinal movement to pick up and discharge the slack away from the face.

13. In a mining apparatus, a mining machine including a machine casing and a laterally projecting cutter bar at one end thereof, and slack handling mechanism connected to said machine and disposed angularly adjacent said bar wholly outside the coal face and at the opposite side of said bar from said casing for discharging slack laterally away from the face and out of the path of the machine.

14. In a mining apparatus, a mining machine including a machine casing and a lat-

- erally projecting cutter bar at one end thereof, and slack handling mechanism connected to said machine and disposed adjacent said bar on the opposite side thereof from said casing and in longitudinal alinement with said casing, said slack handling mechanism including means whereby slack disposed directly in front of a face in which the kerf is being cut is moved laterally of the face and out of the path of the machine.
15. In a mining apparatus, a mining machine including a machine casing and a laterally projecting cutter bar at one end thereof, and slack handling mechanism connected to said machine and disposed adjacent said bar on the opposite side thereof from said casing and within the lines of said casing to move the slack laterally of the face and out of the path of the machine.
20. 16. In a mining apparatus, kerf cutting mechanism movable along a face in which a kerf is being cut, and slack handling mechanism connected to said kerf cutting mechanism and disposed adjacent and outside of said face for receiving cuttings brought back from the kerf by said cutting mechanism and comprising a trailing unit, said unit including an operating mechanism therefor including means for normally moving said slack handling unit bodily relative to said kerf cutting mechanism during operation thereof.
25. 17. In a mining apparatus, kerf cutting mechanism movable along a face in which a kerf is being cut, slack handling mechanism receiving only slack cuttings made thereby and comprising a unit connected to said kerf cutting mechanism and a slack shoveling member movable therewith, and means for moving said unit relative to said kerf cutting mechanism and said shoveling member relative to said unit.
30. 18. In a mining apparatus, a mining machine having a frame carrying a kerf cutting mechanism, and slack handling mechanism connected thereto comprising a self-supported unit and including a slack receiving member movable bodily relative thereto, and self-contained driving connections carried by said slack handling mechanism for normally moving said member bodily relative to said kerf cutting mechanism during operation thereof and independently thereof.
35. 19. In a mining apparatus, kerf cutting mechanism, slack handling mechanism comprising a self-supporting unit connected thereto and including a member movable bodily relative thereto, and driving connections including a motor carried by said slack handling mechanism for moving said member relative to said kerf cutting mechanism.
40. 20. In a mining apparatus, kerf cutting mechanism, slack handling mechanism connected thereto and including a motor and a shovel member adapted to discharge laterally from said mechanism, and operative connec-
- tions to said motor for moving said shovel member toward and from said kerf cutting mechanism and discharging a load from said shovel member.
21. In a mining apparatus, kerf cutting mechanism, slack handling mechanism connected thereto including a motor and a shovel member, and operative connections to said motor for moving said shovel member and slack shoveling mechanism bodily toward and from said kerf cutting mechanism and moving said shovel member relative to said slack shoveling mechanism to discharging position.
22. In a mining apparatus, a mining machine having a casing and cutting mechanism including a horizontal cutter bar angularly disposed relative thereto, said machine being movable along a face in which a substantially horizontal kerf is being cut, and slack handling mechanism connected to said casing and disposed angularly relative to said cutter bar and projecting from said casing to move slack disposed directly in front of the face in which a kerf is being cut laterally thereof and out of the path of the machine.
25. 23. In a mining apparatus, a mining machine comprising a casing movable on a mine bottom, and a horizontal cutter bar angularly disposed relative thereto, said mining machine being movable along a face in which a substantially horizontal kerf is being cut, and slack handling mechanism connected to said casing and disposed parallel to the face and adapted to discharge slack laterally of the face and out of the path of the machine.
30. 24. In a mining apparatus, a mining machine comprising a casing movable on a mine bottom and a horizontal cutter bar angularly disposed relative thereto, said mining machine being movable along a face in which a substantially horizontal kerf is being cut, and slack handling mechanism connected to said casing and disposed adjacent to the face for receiving and discharging slack laterally therefrom and out of the path of the machine.
35. 25. In a mining apparatus, a mining machine movable on a mine bottom and along a face in which a kerf is being cut and having a cutter bar angularly disposed relative thereto, and slack handling mechanism connected to said machine and disposed adjacent to the face and machine and wholly outside of the face, said mechanism being adapted to receive slack brought back from the kerf by said cutter bar and discharge the slack laterally from the face and out of the path of the machine.
40. 26. In a mining apparatus, a mining machine comprising a casing movable on a mine bottom, a cutter bar angularly disposed relative thereto, said machine being movable along a face in which a kerf is being cut, and

slack handling mechanism connected to said casing projecting from said casing, said slack handling mechanism operating wholly outside of and adjacent the face and receiving the slack brought back from the kerf by said cutter bar and discharging the slack laterally from the face and out of the path of the machine.

27. In a mining apparatus, kerf cutting mechanism including a casing, slack handling mechanism operatively connected thereto and in alignment therewith for discharging slack laterally of the face in which a kerf is being cut and out of the path of the apparatus, said slack handling mechanism being disposed wholly outside the face, and a cutter bar carried by said casing having a portion substantially parallel to said slack handling mechanism in a direction at substantially right angles to the face and disposed intermediate the remote ends of said casing and slack handling mechanism.

28. In a mining apparatus, kerf cutting mechanism movable along a face in which a kerf is being cut, slack handling mechanism, disposed wholly outside the face for receiving the cuttings brought back from the kerf by said cutting mechanism, said mechanisms each forming a self-supporting unit normally bodily movable relative to each other during operation thereof, and means to operatively connect said mechanisms together.

29. The combination with a mining machine movable along a face in which a kerf is being cut and having kerf cutting mechanism, of means operatively connected to said machine and disposed adjacent to and wholly outside of the face for receiving and discharging the slack brought back from the kerf by said cutting mechanism and disposed directly in front of the face laterally thereof and out of the path of the machine.

30. The combination with a mining machine movable along a face in which a kerf is being cut and having kerf cutting mechanism, of slack handling means disposed wholly outside the face and connected to said machine to trail the same along the face and to receive and move the slack brought back from the kerf by said cutting mechanism laterally of the face and out of the path of the machine.

31. The combination with a mining machine movable along a face in which a kerf is being cut including kerf cutting means for discharging the cuttings from the kerf, of slack handling mechanism connected to said machine and disposed adjacent and wholly outside of the face to further displace cuttings in the same direction as their initial discharge out of the path of the machine, the advancing side of said slack handling mechanism being disposed behind the trailing side of said cutting mechanism.

32. The combination with a mining machine movable along a face in which a kerf is being cut including kerf cutting means adapted to discharge the cuttings from the kerf, of slack handling mechanism connected to said machine and disposed wholly outside the face, said slack handling mechanism having a portion disposed behind the trailing edge of said cutting mechanism for receiving the cuttings and discharging the same out of the path of the machine in a direction parallel to said cutting means.

33. The combination with a mining machine movable along a face in which a kerf is being cut including kerf cutting means for discharging the cuttings from the kerf, of slack handling mechanism connected to said machine and disposed wholly outside the face, said slack handling mechanism being adapted to receive the cuttings and move the same only laterally from the face and out of the path of the machine.

34. The combination with a mining machine movable along a face in which a kerf is being cut including kerf cutting means for discharging the cuttings from the kerf, of a self-contained slack handling mechanism connected to said machine for receiving the cuttings, and means for normally bodily moving said mechanism relative to said machine during operation thereof to handle the slack cuttings.

35. The combination with a mining machine movable along a face in which a kerf is being cut including the usual casing and cutter bar, of slack handling mechanism disposed wholly outside the face and connected to said machine for discharging the slack cuttings laterally of the face and out of the path of the machine, said mechanism being disposed substantially adjacent the intersection of said bar and casing and whose advancing edge is disposed behind a portion of the trailing edge of the cutter bar.

36. The combination with a mining machine movable along a face in which a kerf is being cut including the usual casing and cutter bar, of slack handling mechanism disposed wholly outside the face and connected to said machine and having a portion of its advancing edge disposed behind a portion of the trailing edge of the cutter bar, said mechanism being disposed substantially adjacent the intersection of the bar and casing for discharging cuttings created by the cutter bar laterally from the face and out of the path of the machine.

37. The combination with a longwall mining machine including kerf cutting means, of slack handling mechanism for discharging slack laterally of the face in which a kerf is being cut, means for normally effecting bodily movement of said mechanism relative to said machine during operation thereof including tension members connecting

said mechanism and machine, and means for detachably securing said members to said machine.

38. Slack handling mechanism forming a self-contained unit for detachable connection to a mining machine comprising relatively movable members one of which is adapted to handle slack, means including a motor carried by one of said members for actuating the other, and means driven by said motor for effecting bodily movement of said mechanism relative to the mining machine during its operation.

39. Slack handling mechanism forming a self-contained unit for detachable connection to a mining machine comprising relatively movable members one of which is adapted to handle slack, means including a motor carried by one of said members for imparting to the other thereof a lateral motion, and means driven by said motor for effecting bodily movement of said mechanism relative to the mining machine during its operation.

40. Slack handling mechanism forming a self-contained unit for detachable connection to a mining machine comprising relatively movable members, means including a motor carried by one of said members for imparting to the other thereof a lateral motion to discharge slack carried thereby, and means driven by said motor for effecting bodily movement of said mechanism relative to the mining machine during its operation.

41. Slack handling mechanism forming a self-contained unit for detachable connection to a mining machine comprising a movable member, means adapted to operatively connect the same to a support, means including a motor carried by said mechanism for moving the same relative to said connecting means, and means driven by said motor for effecting bodily movement of said mechanism relative to the mining machine during its operation.

42. Slack handling mechanism comprising relatively movable members having means adapted to connect the same to a support, and means carried by one of said members for imparting in separate planes lateral curvilinear and longitudinal rectilinear movement successively to the other member relative to said connecting means.

43. Slack handling mechanism forming a self-contained unit for detachable connection to a mining machine comprising relatively movable members having means adapted to connect the same to a support, and means carried by one of said members for moving said mechanism relative to said connecting means and one of said members relatively to the other.

44. A slack handling mechanism forming a self-contained unit for detachable connection to a mining machine comprising a shovel,

and means carried by said mechanism for actuating said shovel.

45. A slack handling mechanism comprising a shovel, a support, the shovel being pivoted on an axis extending longitudinally of the support, and means carried by said mechanism for intermittently actuating said shovel to load and unload the same and to permit a substantial period of rest for said shovel between intermittent actuations thereof.

46. Slack handling mechanism forming a self-contained unit for detachable connection to a mining machine comprising a plurality of relatively movable members and including means adapted to be connected to a support, and means carried by said mechanism to cause relative movement at different intervals in a plurality of directions between one of said members and said connecting means.

47. Slack handling mechanism forming a self-contained unit for detachable connection to a mining machine comprising a plurality of movable members one of which handles slack, means whereby said members are adapted to be operatively connected to a support, means carried by one of said members for causing relatively reciprocatory movement between said connecting means and mechanism, and means for imparting a lateral movement to said slack handling member.

48. A slack handling mechanism forming a self-contained unit for detachable connection to a mining machine and comprising a casing, a slack handling member pivoted thereon on a horizontal axis, a motor carried by said casing, and means whereby said motor is adapted to swing said handling member about its horizontal axis.

49. A slack handling mechanism forming a self-contained unit for detachable connection to a mining machine and comprising a casing, a slack handling member pivoted thereon on a horizontal axis, a motor carried by said casing, and means whereby said motor is adapted to swing said handling member about its horizontal axis and to also move the same rectilinearly in a direction parallel with said axis.

50. A slack handling mechanism forming a self-contained unit for detachable connection to a mining machine and comprising a casing, a slack handling member pivoted thereon on horizontal axis, a motor carried by said casing, and means whereby said motor is adapted to swing said handling member about its horizontal axis, said means including a lost-motion connection.

51. A slack handling mechanism forming a unit for detachable connection to a mining machine and comprising a casing having a slack guiding nose and a slack handling member onto which said nose directs slack ma-

terial, and means whereby said latter member is adapted to be laterally moved to discharge slack away from the face in which a kerf is being cut.

5. 52. A shoveling device adapted for connection to a mining machine comprising a shovel member, means whereby the same may be moved forwardly relative to said machine to obtain a load, and means whereby said shovel is adapted to be swung about an axis extending generally along the longitudinal axis of said shovel to unload the same.

53. A shoveling device adapted for connection to a mining machine comprising a shovel member, means whereby the same may be moved forwardly relative to said machine to obtain a load, and means whereby said shovel is adapted to be automatically rotated after it is loaded about an axis extending generally along the longitudinal axis of said shovel to unload the same laterally.

54. In a mining apparatus, mechanism for handling loose coal lying adjacent a coal face comprising a body movable longitudinally of the coal face, means on the advancing side of said body and disposed wholly outside the

face for collecting loose coal, and means comprised in said collecting means for periodically discharging the collected material laterally of the advancing body. 30

55. In a mining apparatus, a self-contained kerf cutting mechanism movable along a face in which a kerf is being cut, and a self-contained independently powered conveying mechanism disposed wholly outside the face 35 and connected to said kerf cutting mechanism for moving loose coal laterally away from the face.

56. In a mining apparatus, a cutting unit adapted to cut a kerf in a coal face, an independently powered conveying unit disposed wholly outside the face, and operative connections between said units. 40

57. In a mining apparatus, a cutting unit adapted to cut a kerf in a coal face, a conveyor unit disposed wholly outside the face, and connections between said units for moving the same bodily relative to each other during normal operation thereof. 45

In testimony wherof I affix my signature.

MORRIS P. HOLMES.
